Primary Examiner — Darlington Ly(74) *Attorney, Agent, or Firm* — Shumaker, Loop & Kendrick, LLP(57) **CLAIM**

The ornamental design for a wheel rim, as shown and described.

DESCRIPTION

FIG. 1 is a perspective view of a wheel rim embodying my new design; and,

FIG. 2 is a front elevation view thereof.

In the drawings, the broken lines represent portions of the wheel rim that form no part of the claimed design.

1 Claim, 2 Drawing Sheets(56)
